UNITED STATES PATENT OFFICE

RAYMOND N. EHRHART, OF PITTSBURGH, PENNSYLVANIA, ASSIGNOR TO ELLIOTT COMPANY, OF PITTSBURGH, PENNSYLVANIA, A CORPORATION OF PENNSYLVANIA

APPARATUS FOR EVAPORATING LIQUID

Application filed June 3, 1926. Serial No. 113,428.

The present invention relates broadly to the art of liquid treatment, and more particularly to an improved apparatus for effecting the recovery of waste heat, and utilizing such heat for evaporating liquid.

It is well recognized in the art to which my invention broadly relates, that in the utilization of high pressure steam for the development of energy in mechanical or other forms, the steam in passing through the apparatus with which it is being utilized, gives up a certain portion of its thermal energy. The portion so given up to the apparatus is in turn converted thereby into another form of energy, such, for example, as mechanical energy. The greater portion of the thermal energy of steam is not utilized by the apparatus, so that the discharge therefrom, or the steam rejected thereby, carries by far the greater part of the original thermal energy. In other words, the thermal energy in the exhaust of an apparatus such, for example, as a steam engine, is usually many times that which has been utilized by the engine, and this thermal energy of exhaust steam is usually spoken of as degraded or low level heat.

In accordance with standard principles of operation, in order to obtain the maximum range for the utilization of heat, it is desirable to have the engine discharge or exhaust into a region of the lowest possible pressure, which, with steam, means the lowest possible temperature. A condenser is an artifice generally utilized to create such a region of low temperature and pressure, the temperatures maintained by the condenser being generally so low that there is no way to utilize all of the low level heat in the range as maintained by the condenser. I have found that it is possible to reclaim small portions of the low level heat which have heretofore ordinarily been rejected to the condenser, and the present invention has to do particularly with this reclaiming and utilization of such portions of the heat.

In the accompanying figure of the drawing, which figure is largely diagrammatical, there is illustrated one embodiment of the present invention, which embodiment com-

prises the combination of a condenser and evaporator in which the heat for evaporation is supplied by exhaust steam, the heat of which under ordinary conditions of operation would normally be given to the condensing water of the main condenser.

In carrying out the present invention, there may be provided a main condenser 2, having a header at one end, divided by a transverse partition 3, whereby cooling water delivered to the condenser through the connection 4 passes through the tubes 5 in the lower portion of the condenser in one direction and through the tubes 6 in the upper portion of the condenser in the opposite direction. After having absorbed a certain amount of heat from the vapor delivered to the condenser through the vapor inlet 7, the water is discharged in large part through an off-take 8, and led to a suitable point.

Above the tube nest 6 I provide a partition 9 above which are located two supplemental tube nests 10 and 11. That portion of the cooling water which is not discharged through the off-take 8 passes upwardly to the tubes 10, and flows therethrough to the opposite end of the condenser. It is then returned through the tubes 11, discharging into the supplemental water off-take 12. It will be apparent that the tube nests 10 and 11 are so located that they are directly exposed to the steam entering the main condenser through the inlet 7. It is usually found that tubes first facing the vapor flow have the highest heat transfer, and those farthest removed from the vapor flow, the lowest heat transfer. Under such conditions, the tubes in the nests 10 and 11 will have a more efficient heat transfer than the tubes in any other part of the main condenser. By selecting proper water quantities and flow velocities through these two nests of tubes, I can obtain such an efficient transfer of heat from the vapor to the water passing therethrough that the water leaving through the supplemental connection 12 will have a temperature almost equal to that of the temperature of the vapor delivered to the condenser.

In other words, I preferably so proportion the entire condenser that the

temperature of the portion of the raw water delivered through the inlet 4, and leaving through the supplemental outlet 12, is almost equal to the temperature of the steam.

5 I also preferably provide a second condenser 13, which will hereinafter be referred to as a high vacuum condenser. This condenser is of much smaller size than the main condenser, and differs fundamentally from 10 the operation of the auxiliary tube nests 10 and 11 in that while the auxiliary tube nests function to deliver water at a temperature approximating as closely as possible the temperature of the supplied vapor, the 15 condenser 13 operates to maintain as high a vacuum as possible. This vacuum in all cases must be greater than the vacuum maintained by the main condenser.

I find that it is possible to so proportion 20 the high vacuum condenser in regard to surface, water circulation and the like, that it is practically possible to always maintain a vacuum, the incident steam temperature of which is from 10 to 15° less than that of the co-incident vacuum in the main condenser.

In view of the desirability of maintaining 30 the highest possible order of vacuum in the high vacuum condenser 13, I preferably supply a very liberal amount of cooling water thereto, through the connection 14 and discharge the same through the connection 15. Also, the high vacuum condenser is preferably equipped with gas exhausting means 35 of great capacity, such means conveniently comprising a multi-stage ejector 16, as well understood in the art.

For purposes of illustration only, it may 40 be pointed out that in ordinary operation a main condenser of the general character herein disclosed might be supplied with cooling water at a temperature of 50° F., which water will be raised to a temperature of approximately 65° F., and discharged at this 45 temperature from the condenser.

Under such conditions a steam temperature 50 of 75° might be maintained in the steam inlet of the condenser. In such cases, the small portion of water flowing through the auxiliary tube nests may have a temperature 55 of approximately 73° F., which temperature closely approximates the temperature of the supplied steam. With temperature conditions of the character referred to, the high 60 vacuum condenser might be so proportioned that with the same temperature of cooling water, it would have a discharge temperature of 55°, thereby maintaining a vacuum such that the steam temperature at its inlet 17 would correspond to 60° F. The foregoing 65 values are not given as representing the absolute performance of such an apparatus, but are typical of the general temperature ranges that is is desired to obtain, and which 70 may be obtained and maintained with an

apparatus of the general nature herein disclosed. If the apparatus is so operated that the high vacuum condenser maintains a steam temperature of 60° while the main condenser maintains a steam temperature of 75°, and the auxiliary tube nests deliver water at a temperature of approximately 73°, there is a temperature gradient of 13° between the temperature of the water passing through the supplemental outlet 12 and the temperature at the inlet 17 of the high vacuum condenser. This temperature gradient may be very effectively utilized for flashing a portion of the water passing through the supplemental outlet 12 at the expense of 75 its contained heat.

Such flashing may conveniently be obtained by providing a flash chamber 18 having its vapor space operatively connected to the inlet 17 of the high vacuum condenser and constructed to receive cooling water from the auxiliary tube nests of the main condenser through the supplemental outlet 12. With such a construction, the water coming into the flash chamber will immediately violently boil, due to its excess heat above the natural boiling temperature of 60° maintained in the flash chamber by the high vacuum condenser, and a certain portion will consequently be carried over into the high vacuum condenser wherein condensation will take place to change the same from its vapor phase to its liquid phase as distilled water. This distilled water may be conveyed to any desired point, as, for example, the hot well 19 of the main condenser through a manometric loop 20, or it may be pumped out of the high vacuum condenser or otherwise removed therefrom and delivered to any desired point.

The cooling water discharged from the high vacuum condenser may be delivered to any desired point, but conveniently it is delivered to the same point as that to which the cooling water discharged from the main condenser through the outlet 8 is delivered. The water from the flash chamber 18 may be removed therefrom in any desired manner, such as by a centrifugal pump 21 and discharged to the same point.

It will be apparent from the foregoing that I provide an improved method and apparatus by means of which raw water is evaporated by low level heat in the vapor introduced into the main condenser. It is true that some steam will be required for the operation of the multi-stage ejector for the high vacuum condenser, but this is of relatively small amount in comparison with the heat required for the evaporation of water, and the heat of such steam as is used in the multi-stage ejector may be effectively recovered by passing condensate through the condensers at the termini of the respective ejector stages.

Certain advantages of the present inven- 120

tion arise from the provision of a method and apparatus by means of which a portion of the low level heat may be recovered and effectively utilized instead of discarding the same, as has heretofore been practiced.

Other advantages of the invention arise from the provision of a main condenser having auxiliary tube nests of such construction that temperature conditions therein may approximate the temperature conditions of the supplied steam, and delivering water from such tube nests to a flash chamber in which is maintained a flash temperature gradient sufficient to effect flashing of a portion of the liquid so delivered.

Still further advantages arise from the combination of a flash chamber receiving water heated by low level heat to substantially the temperature of the exhaust steam, and having relatively low pressure maintained therein by suitable means, such as a high vacuum condenser.

I have described a preferred embodiment of the invention, but it will be understood that it is not to be limited, since it may be otherwise embodied or practiced within the scope of the following claims:

I claim:—

1. Evaporating apparatus comprising a main condenser, auxiliary heating tubes within the condenser and subjected to the pressure conditions therein, means for passing a portion of the cooling water for said condenser through said auxiliary tubes, a flash chamber means for delivering the water from said auxiliary tubes to the flash chamber, and means for maintaining in said flash chamber a pressure lower than the pressure in the vapor space of said condenser.

2. Evaporating apparatus comprising a main condenser, auxiliary heating tubes within the condenser and subjected to the pressure conditions therein, means for passing a portion of the cooling water for said condenser through said auxiliary tubes, a flash chamber means for delivering the water from said auxiliary tubes to the flash chamber, and means for maintaining in said flash chamber a pressure lower than the pressure in the vapor space of said condenser, said last named means comprising a high vacuum condenser.

3. Evaporating apparatus comprising a main condenser, auxiliary heating tubes within the condenser and subjected to the pressure conditions therein, means for passing a portion of the cooling water for said condenser through said auxiliary tubes, a flash chamber means for delivering the water from said auxiliary tubes to the flash chamber, and means for maintaining in said flash chamber a pressure lower than the pressure in the vapor space of said condenser, said last named means comprising a high vacuum

condenser in combination with gas exhausting means.

4. Evaporating apparatus comprising a main condenser having main tubes and auxiliary tubes within the condenser and subjected to the pressure conditions therein connected to provide a series flow of water therethrough, means for admitting water first to the main tubes, means intermediate the main and auxiliary tubes for taking off a portion of such water and permitting only a portion thereof to pass through the auxiliary tubes, and means for producing a steam flow in series over said tubes.

5. Evaporating apparatus comprising a main condenser having main tubes and auxiliary tubes within the condenser and subjected to the pressure conditions therein connected to provide a series flow of water therethrough, means for admitting water first to the main tubes, means intermediate the main and auxiliary tubes for taking off a portion of such water and permitting only a portion thereof to pass through the auxiliary tubes, and means for producing a steam flow in series over said tubes, with the steam contacting first with the auxiliary tubes.

6. Evaporating apparatus comprising a main condenser having main tubes and auxiliary tubes within the condenser and subjected to the pressure conditions therein connected to provide a series flow of water therethrough, means for admitting water first to the main tubes, means intermediate the main and auxiliary tubes for taking off a portion of such water and permitting only a portion thereof to pass through the auxiliary tubes, said auxiliary tubes having a higher heat transfer co-efficient than the main tubes, and means for producing a steam flow in series over said tubes.

7. Evaporating apparatus, comprising a main condenser casing having an inlet for a vapor mixture, main tubes and auxiliary tubes in said casing both subjected to the pressure conditions obtaining in the condenser and constructed to provide a series flow of water therethrough with the flow first through the main tubes, said auxiliary tubes being disposed adjacent said inlet with the main tubes remote therefrom, and means intermediate the main and auxiliary tubes for taking off a portion of the water and permitting only a portion to pass through the auxiliary tubes.

In testimony whereof I have hereunto set my hand.

RAYMOND N. EHRHART.
